UNITED STATES PATENT OFFICE.

PHILIP SUKROW, OF DETROIT, MICHIGAN, ASSIGNOR TO JOSEPH V. BOEMER, OF DETROIT, MICHIGAN.

REVERSIBLE COLLAR.

Application filed July 14, 1926. Serial No. 122,415.

The invention relates to reversible collars of the soft or semi-stiff fold over type. Collars of this type as heretofore made have been found impracticable owing to the fact that the construction of the collar was such that the fold over top did not properly fold over upon the band in both directions. With my invention the collar is readily reversible and presents a neat and pleasing appearance with either side outermost. This is obtained by forming the collar of two separate plies and by stitching the band forming portions of these plies to a reinforcement and by stitching the edges only of the fold over top forming portions of these plies to each other in a manner to form a comparatively stiff band and to provide a fullness in the fold over top with the result that the collar not only readily and properly folds in either direction but the top also readily conforms to the band when the collar is in use. Other objects of the invention reside in the novel features of construction as more fully hereinafter set forth.

In the drawings:—

Figure 1 is a plan view of a reversible collar embodying my invention;

Figure 2 is a cross section on the line 2—2 of Figure 1;

Figure 3 is a similar cross section showing the collar folded.

1 and 2 are two separate complementary plies of fabric each having the lower portion 3 and the upper portion 4 respectively forming a portion of the band and a portion of the fold over top. To provide for readily and properly folding over the top in either direction upon the band, the band is made comparatively stiff and the top is made full. As shown, I have provided the reinforcement 5 between and co-extensive with the band forming portions 3 and having the folded over upper edge 6, the fold line of which establishes the fold line of the collar. For securing the plies 1 and 2 to each other and the reinforcement to the band forming portions 3, I stitch the edges of the plies 1 and 2 to each other with the exception of the central portions of the lower edges of the band forming portions 3 by the zig-zag stitching 7. This stitching also secures the lower edge of the reinforcement to the lower edges of the band forming portions 3. After zig-zag stitching, the collar is turned

inside out and its edges are stitched by the two rows of stitching 8 and its band forming portions 3 are stitched to the reinforcement 5 by the series of rows of stitching 9 which extend longitudinally of the band forming portions with the upper row slightly below the fold line of the reinforcement. The stitching of the band forming portions to the reinforcement by the series of rows of stitching 9 makes the band of the collar 65 comparatively stiff. The stitching of the band forming portions and reinforcement shortens the band and the stitching of the edges of the top forming portions to each other forms in effect a frame for the fold over top with the stitching of the upper edges of the top forming portions also shortening these upper edges so that fullness is provided in the parts of the top forming portions surrounded by the stitching where 70 by the top formed thereby may readily and properly fold over upon the band in either direction and also readily conform to the band when the collar is in use. In connection with the shortening of the upper edges 75 of the top forming portions, both the zig-zag stitching 7 and the stitching 8 produce a shortening effect. This folding over is also facilitated by the fact that the top forming portions are secured only at their 80 edges so that one portion may move relative to the other to a certain extent when the collar is being folded over and is further facilitated by reason of the zig-zag stitching 7 and the stitching 8 forming a reinforcement 85 edge for the top.

The tabs 10 at the ends of the collar band are similarly shaped and the button hole stitching 11 in these tabs is finished on opposite sides of the band so that the tabs may 90 occupy their correct positions and the finished side of the button hole stitching may be outermost when either side of the collar is outermost.

What I claim as my invention is:

1. A reversible collar comprising two separate plies having cooperating band and fold over top forming portions, a reinforcement between the band forming portions of said plies having a folded over edge for 100 establishing the fold line of the collar, and means for securing the band forming portions of said plies and said reinforcement together and for also securing the fold over top portions of said plies together at their 105

110

edges only in a manner to form a comparatively stiff band and also to provide a fullness in the fold over top whereby the latter folds readily in either direction upon and conforms to the band.

2. A reversible collar comprising two separate plies having cooperating band and fold over top forming portions, a reinforcement between and substantially co-extensive with the band forming portions of said plies having a folded over edge for establishing the fold line of the collar and rows of stitching for securing the band forming portions of said plies and said reinforcement together and for also securing the fold over top portions of said plies together at their edges only in a manner to form a comparatively stiff band and also to provide a fullness in the fold over top whereby the latter folds readily in either direction upon and conforms to the band.

3. A reversible collar comprising two separate plies having cooperating band and fold over top forming portions, and means providing a fullness in the fold over top and a comparatively stiff band, said means comprising a reinforcement between and substantially co-extensive with the band forming portions having a folded over edge for

establishing the fold line of the collar, means including zig-zag stitching for securing the edges of the top forming portions together and series of rows of stitching extending longitudinally of the band forming portions for securing the reinforcement thereto.

4. A reversible collar of the semi-stiff fold-over type comprising two separate plies having cooperating band and fold-over top forming portions, a reinforcement between and substantially co-extensive with the band forming portions having a folded over edge for establishing the fold line of the collar, a series of rows of stitching extending longitudinally of the band forming portions for securing the reinforcement thereto and shortening the band formed thereby, stitching for securing the edges only of the fold-over top forming portions to each other and forming in effect a frame for the fold over top, said stitching and series of rows of stitching providing a fullness in the parts of the top forming portions surrounded thereby so that the fold-over top readily and properly folds in either direction and conforms to the band.

In testimony whereof I affix my signature.

PHILIP SUKROW.
